UNITED STATES PATENT OFFICE.

NELS JORGENSEN, OF CRAIG, NEBRASKA.

LOADING APPARATUS.

No. 826,035.

Specification of Letters Patent.

Patented July 17, 1906.

Application filed April 19, 1906. Serial No. 312,587.

To all whom it may concern:

Be it known that I, NELS JORGENSEN, a subject of the King of Denmark, residing at Craig, in the county of Burt and State of Nebraska, have invented certain new and useful Improvements in Loading Apparatus, of which the following is a specification.

This invention relates to loading apparatus in general, and it has particular reference to an improved apparatus whereby heavy and bulky material, such as manure and compost, may be loaded into wagons, the special object of the invention being to provide an apparatus of this class of simple and improved construction, whereby an entire wagon-load may be deposited upon a platform that constitutes a part of the loading apparatus, means being provided whereby said platform may be elevated and tilted so as to discharge its contents into the body or box of a wagon which is driven to receiving position beneath the platform.

Further objects of the invention are to simplify and improve the general construction and operation of this class of apparatus.

With these and other ends in view, which will readily appear as the nature of the invention is better understood, the same consists in the improved construction and novel arrangement and combination of parts, which will be hereinafter described, and particularly pointed out in the claims.

In the accompanying drawings there has been illustrated a simple and preferred form of the improved apparatus, it being, however, understood that no limitation is necessarily made to the precise structural details therein described, but that changes, alterations, and modifications within the scope of the invention may be resorted to when desired.

In the drawings, Figure 1 is a perspective view of the improved loading apparatus, showing the same in load-receiving position.

Fig. 2 is a side elevation showing the apparatus with the load-carrying platform elevated, dotted lines being employed to indicate the platform in a tilted or load-discharging position and also to indicate the several parts of the apparatus in load-receiving position.

Fig. 3 is a top plan view showing the apparatus in load-receiving position.

Corresponding parts in the several figures are designated by like characters of reference.

The improved apparatus includes a base-

frame B, the side members of which consist of skids or runners 11, which are suitably connected and spaced apart at intervals by means of cross-pieces 22. Said side members are also connected by means of obliquely-disposed brace-rods 33.

Pivotedly connected with the side members 11 of the base-frame, as by means of a transverse bolt or connecting member 4, are the side members 55 of a lifting-frame L, which said side members are securely connected by means of obliquely-disposed brace-rods 66'. The bolt or connecting member 4 affords a fulcrum for a lever-frame consisting of converging side members 66. The apex of the lever-frame is connected with the side members 55 of the lifting-frame L by means of rods or connecting members 77, the lever-frame being disposed approximately at right angles to the lifting-frame, so that when the latter lies flat upon the ground, as shown in Fig. 1 of the drawings, the lever-frame will occupy an approximately perpendicular position.

The load-receiving platform P is composed of suitable flooring 8, secured upon a pair of cleats or flange members 99, whereby the flooring is slightly elevated above the ground when the platform occupies the load-receiving position indicated in Fig. 1. At the inner edge of the platform is an upstanding flange 10, which prevents material from being split over the said inner edge, and the front and rear edges of the platform are provided with inclined approaches 11 to enable scrapers of ordinary construction to be utilized in depositing material upon the platform for loading into wagons.

It is to be understood that within the scope of the invention the construction of the platform may be modified to the extent of providing such bracing and reinforcing means as may be deemed necessary to provide a construction of the requisite strength and durability.

The platform is connected with the lifting-frame L, as by means of a bolt or connecting member 12, extending through the extremities of the side members 55 of the lifting-frame and through the cleats or flanges 9 upon the under side of the platform, the arrangement being such that the pivotal member 12 shall be disposed nearer the inner than the outer edge of the platform. It follows that the outer portion of the platform will overbalance the inner portion of the same, this being obvi-

ously desirable to insure convenience in tilting the platform for the discharge of the load from said platform into the box or body of a wagon, as will be presently more fully described.

- 5 For the purpose of sustaining the floor of the platform in an approximately horizontal or level position while the load is being elevated the inner edge of the platform is connected by a link-bar 15 with the base-frame, preferably through the medium of one of the cross-bars 2 of said base-frame, with which the said link-bar is hingedly connected, as by means of interengaging eyebolts 16. The 10 upper or outer end of the link-bar is detachably connected with the platform by means of a flexible element, such as a wire rope or cable 17, which is guided over a pulley 18 near the upper or outer end of the link-bar, 15 one end of said flexible element being attached to the platform and the opposite end thereof being adapted to be detachably connected with the link-bar, as by means of a cleat 18.
- 20 25 Near the free end of the lever-frame there is supported a block or pulley 19, and a similar block or pulley 20 is connected with the cross-bar 2 near the end of the base-frame distant from the lever-frame. A flexible 30 hoisting element 21 is connected with the hanger 22 of the pulley 19, said hoisting element being reeved beneath the pulley 20, over the pulley 19, and finally under a guide-pulley 23, suitably supported upon the base-frame, the terminal end of said flexible element being extended to the point of attachment of the draft. As will be readily understood, power of any well-known description 35 may be utilized for the purpose of operating 40 the device.

From the foregoing description, taken in connection with the drawings hereto annexed, the operation and advantages of this invention will be readily understood. Material that is to be loaded upon wagons—such as manure, compost, sand, gravel, or the like—may be gathered by means of horse-scrapers of ordinary construction and deposited upon the platform. When a sufficient quantity to 45 form a load has been placed upon the platform, draft is applied to the hoisting element 21, thus exerting stress in a downward direction upon the elevated free end of the lever-frame, the stress being communicated 50 through the connecting members 7 to the lifting-frame L, which latter ascends as the lever-frame approaches a recumbent or approximately horizontal position. As the 55 free end of the lifting-frame is being elevated 60 it elevates the loaded platform, the approximately horizontal position of which is maintained by means of the link-bar 15. When the proper elevation has been attained, an empty wagon is driven beneath the platform; 65 and the free end of the flexible element 17 is

then cast loose, thus causing the platform to be automatically tilted by the preponderance of weight upon the outer portion of said platform, the load being discharged directly into the wagon beneath. As soon as the load has 70 been discharged from the platform the latter is restored to its normal approximately horizontal position by simply pulling the flexible member 17, the latter being made fast, as before, for the purpose of securing the platform. 75 The strain upon the draft element 21 is now released, and the platform will then gravitate to its initial load-receiving position.

As will be seen from the foregoing description and from the accompanying drawings 80 this improved loading apparatus is extremely simple in construction, and it may therefore be manufactured at a moderate expense. Its construction is such that heavy loads may be elevated and discharged into wagons with 85 great facility and with comparatively slight expenditure of power.

Having thus described my invention, I claim and desire to secure by Letters Patent of the United States— 90

1. In a loading apparatus a base-frame; a platform, a lifting-frame connected pivotally with the platform intermediate the edges of the latter and connected pivotally with the base-frame near one end of the latter, a link-bar connected pivotally with the base-frame, and means for connecting said link-bar detachably with the platform near one edge of the latter. 95

2. In a loading apparatus a base-frame, a platform, parallel members connecting the platform with the base-frame one of said parallel members being detachably connected with one edge of the platform, a lever-frame supported approximately at right angles to 100 the lifting-frame and suitably connected with the latter, and means for applying draft to the free end of the lever-frame. 105

3. In a loading apparatus a base-frame, a load-receiving platform including cleats or 110 braces and flooring secured upon said cleats or braces and thereby elevated above the ground when the platform is in load-receiving position, a lifting-frame connecting the platform with the base-frame said lifting-frame being connected pivotally with the cleats of the platform intermediately the ends of said cleats, a link-bar connected hingedly with the base-frame and provided with guiding means near its opposite end, 115 and a flexible element connected with one edge of the platform, guided over the guiding means upon the link-bar, and adapted to be made fast upon the latter. 120

4. In a loading apparatus a base-frame, a platform including cleats or braces, flooring secured upon said cleats, an upstanding flange at the inner edge, and inclined approaches at the front and rear ends of said platform, a lifting-frame connected pivotally 125 to

with the cleats of the platform and with the base-frame, a link-bar connected hingedly with the base-frame and having a guide member near its free end, a flexible member 5 connected with the inner edge of the platform and guided over the guiding member to a point of attachment upon the link-bar, a lever-frame supported approximately at right angles to the lifting-frame and connected 10 with the latter, and means for applying draft to the lever-frame.

5. In a loading apparatus a base-frame, a fulcrum member extending through the side members of the base-frame, a lever-frame 15 consisting of converging side members pivoted upon the fulcrum member, a lifting-frame having side members pivoted upon said ful-

crum member, rods connecting the apex of the lever-frame with the side members of the lifting-frame and maintaining said frames 20 approximately at right angles to each other, a platform supported pivotally at the free end of the lifting-frame, a link-bar connected hingedly with the base-frame and detachably with one edge of the platform said link-bar 25 being approximately parallel to the lifting-frame, and means for applying draft to the front end of the lever-frame.

In testimony whereof I affix my signature in presence of two witnesses.

NELS JORGENSEN.
